UNITED STATES PATENT OFFICE.

GEORGE A. AWALT, OF MINNEAPOLIS, MINNESOTA.

ADJUSTABLE STORM-WINDOW HOLDER.

Application filed November 22, 1920. Serial No. 425,658.

To all whom it may concern:

Be it known that I, GEORGE A. AWALT, a citizen of the United States, residing at Minneapolis, in the county of Hennepin and State of Minnesota, have invented certain new and useful Improvements in Adjustable Storm-Window Holders; and I do hereby declare the following to be a full, clear, and exact description of the invention, such as will enable others skilled in the art to which it appertains to make and use the same.

This invention relates to a window holder and is particularly designed to be used with a storm window or other outside window or screen structure. In the colder portions of a country, storm windows are used during the winter season and such windows are usually secured in position by being hinged or pivoted at their upper ends. These windows are only opened slightly and when so open are merely swung outwardly at their bottom portion.

It is an object of this invention to provide a holder for such windows, whereby the same can be opened to any desired extent and held firmly in such position. This and other advantages of the invention will be apparent from the following description made in connection with the accompanying drawings, in which like reference characters refer to the same parts throughout the different views, in which—

Fig. 1 is a top plan view of the device, a portion of the window being shown in section and an extended position of the device being shown in dotted lines;

Fig. 2 is a view in elevation of the device as seen from the right of Fig. 1; and

Fig. 3 is a somewhat diagrammatic view showing a hinged storm window with the device of the invention in relation thereto, said window being shown in an open position by dotted lines.

Referring to the drawings:

The device is seen to consist of a plate 1, having a raised central portion and apertured end portions adapted to receive attaching screws by which the plate is firmly secured to the sill or outer portion of the window frame. This plate is also provided with an aperture at its central raised portion and a headed screw 2 is disposed in this aperture, its threaded portion of which extends upwardly and receives in superposed relation above said plate, the apertured ends of two flat link members 3 and 4. A washer

is also placed on the screw 2 above the upper link and a winged clamping nut 5 is threaded on the screw above the washer. The links 3 and 4 extend in opposite directions 60 and have pivoted thereto at their outer ends the ends of similar links 5 and 6. The links 5 and 6 are also oppositely disposed and in the closed position of the device shown in Fig. 1 extend at a slight angle to the links 3 and 4 to form a closed parallelogram. The other ends of links 5 and 6 are apertured and in alignment and are pivoted to an apertured lug extending from the bottom of a plate member 7, which is provided with 70 suitable holds for attachment to the lower sash 8 of the window. The upper portion of the member 7 is tapered and rounded at its end and bent outwardly in a curve to form a suitable finger hold for manipulating 75 the window. The operation of the device is as follows:

The window 8 which as shown in Fig. 3 is pivoted at its upper portion will be swung outwardly to the desired position by operator grasping the finger hold of member 7. The links will then swing on their various pivots and being distended as shown in Fig. 1. These links, it will be noted, form a lazy tong structure. When the window is 85 open to the desired position, the clamp nut 5 which previously has been loosened, will now be tightened. The window will be held securely in the desired position. As desired, the portion of the link 3 which contacts with plate 1 and link 4 may be somewhat loosened or corrugated so that when the screw 5 is tightened the parts will be firmly held in frictional engagement.

It is thus seen that the applicant has produced a simple and efficient window holder and one which can be quickly applied and will require very little attention. It will be understood that various changes may be made in the form and details of the device 95 without departing from the scope of the applicants invention, which generally stated consists in the matter shown and described and set forth in the appended claims.

What is claimed is:—

1. A window holder having in combination a bracket adapted to be secured to the window sash, a pair of links pivoted to said bracket and diverging therefrom, a second pair of links pivoted to the ends of said first mentioned links, having their other ends converging, a bracket secured to the window 105 110

frame, and a single bolt forming both the connecting means of said last mentioned links and bracket and a locking means for portion locking said sash in various open positions and also in closed position.

2. The structure set forth in claim 1, said bracket secured to the window sash having a projecting portion to which the first mentioned links are pivoted having an outwardly and downwardly curved portion forming a finger hold for moving said windows;

3. A window holder having in combination, two pairs of plain links pivoted together to form a lazy tong structure, a

bracket adapted to be secured to the window sash to which the ends of one pair of links are pivoted, a bracket adapted to be secured to the window frame, a single pivot connecting the ends of said second pair of links and said latter bracket, said pivot being threaded, and a clamping nut screwed thereon adapted to contact the ends of said links and clamp the same against said bracket to positively lock said sash in various open positions and also in closed position. 25

In testimony whereof I affix my signature.

GEORGE A. AWALT.
